UNITED STATES PATENT OFFICE

156,128

DESIGN FOR A MAGNETIC MEMO HOLDER FOR ATTACHMENT TO TELEPHONES

Harry W. Korb, South Euclid, Ohio

Application November 4, 1948, Serial No. 149,452

Term of patent 3½ years

(Cl. D26—14)

To all whom it may concern:

Be it known that I, Harry W. Korb, a citizen of the United States, residing at South Euclid, county of Cuyahoga and State of Ohio, have invented a new, original, and ornamental Design for Magnetic Memo Holder for Attachment to Telephones, of which the following is a specification, reference being had to the accompanying drawing, forming a part thereof.

Fig. 1 is a top plan view of a magnetic memo holder for attachment to telephones, showing my new design;

Fig. 2 is a front elevational view of the holder;

Fig. 3 is a side elevational view, as viewed from the right side of the holder, and

Fig. 4 is a fragmentary cross-sectional view, taken on the line 4—4 of Fig. 3.

I claim:

The ornamental design for a magnetic memo holder for attachment to telephones, substantially as shown.

HARRY W. KORB.
